US00D687167S

(12) **United States Design Patent**
Mugge et al.

(10) **Patent No.:** US D687,167 S
(45) **Date of Patent:** ** Jul. 30, 2013

(54) **MOLDED SURFACE OF A CONCRETE PRODUCT**

- (71) Applicant: **Anchor Wall Systems, Inc.**, Minnetonka, MN (US)
- (72) Inventors: **Jimmie L. Mugge**, Inver Grove Heights, MN (US); **Jay J. Johnson**, Star Prairie, WI (US); **Robert Joel Wolter**, Chaska, MN (US)
- (73) Assignee: **Anchor Wall Systems, Inc.**, Minnetonka, MN (US)

(**) Term: **14 Years**

(21) Appl. No.: **29/442,007**

(22) Filed: **Nov. 9, 2012**

Related U.S. Application Data

- (62) Division of application No. 29/395,232, filed on Dec. 20, 2011, now Pat. No. Des. 673,693, which is a division of application No. 29/372,509, filed on Nov. 29, 2010, now Pat. No. Des. 653,772.

CLAIM

The ornamental design for a molded surface of a concrete product, as shown and described.

DESCRIPTION

FIG. 1 is a perspective view of a molded surface of a concrete product, according to our design;

FIG. 2 is a front view thereof;

FIG. 3 is a right side view thereof;

FIG. 4 is a left side view thereof;

FIG. 5 is a top view thereof; and,

FIG. 6 is a bottom view thereof.

The broken lines in the drawing views are included for the purpose of illustrating portions of the molded surface of a concrete product that form no part of the claimed design.

1 Claim, 6 Drawing Sheets
